CONCRETE WALL FORM

Thomas Woodrow Wilson, Spokane, Wash.
Application June 8, 1953, Serial No. 360,056

5 Claims. (Cl. 25—131)

My invention relates to improvements in a concrete wall form. These forms to which my invention applies are usually constructed of wood panels and are erected to form two spaced apart supporting walls between which the fluid concrete is poured and held until it sets. The form walls are usually held together by cross tie rods or strips. The problem of making these forms in panels which could be set up and taken down quickly is a difficult one. This is evident from the fact that there are many patented devices which propose to eliminate the difficulties. It is nevertheless true that builders who operate generally on a relatively small scale, use wood panels that are supported and backed up by wooden frame members and the frame members are nailed together. This makes it necessary to pull the nails in taking down the forms and repeated use of such forms is not economical because they soon deteriorate.

The principal purpose of my invention is to provide a wall form assembly which embodies improved devices for securing and protecting the facing sheet, which devices provide the means to clamp two edgewise adjacent panels together, and in addition, provide the means to secure the tie strips which connect the opposite wall forms.

More specifically it is the purpose of my invention to provide a panel which makes a form when connected with like panels and with tie strips, wherein the panel consists of a facing sheet such as plywood with two metal edge strips covering the side edges of the plywood facing sheet, and walers or cross members connecting the edge strips and backing up the facing sheet. The edge strips have flanges spaced from the facing sheet and they are apertured with aligned apertures to receive headed pins for connecting two adjacent panels. One of the edge strips carries the securing pins and the wedges for connecting two panels together, with means for fastening the tie strips that connect to opposite walls of the form. Each of these panels embodying my invention is a complete unit, having all of the necessary parts to attach it to an adjacent panel. The panels are of uniform rectangular dimensions and thickness so that they may be handled just as sheets would be handled in stacking them up and transporting them from one place to another.

The nature and advantages of my invention will appear more fully from the following description and the accompanying drawings in which a preferred form of the invention is illustrated. It should be understood however, that the description and drawings are illustrative only and are not intended to limit the invention except insofar as it is limited by the claims.

In the drawings:

Figure 1 is a side view of a portion of a concrete wall form showing how one panel is joined to two adjacent panels;

Figure 2 is a perspective view of a portion of a panel illustrating the uniformity of the panel structure and the way in which each panel carries its securing means;

Figure 3 is an enlarged plan sectional view taken on the line 3—3 of Figure 1;

2

Figure 4 is a fragmentary sectional view taken on the line 4—4 of Figure 3;

Figure 5 is an enlarged fragmentary sectional view taken on the line 5—5 of Figure 1;

5 Figure 6 is a sectional view taken on the line 6—6 of Figure 5; and

Figure 7 is a fragmentary sectional view taken on the line 7—7 of Figure 2.

Referring now in detail to the drawings and in particular to Figures 1, 2 and 3, my invention is shown as embodied in a panel assembly wherein a plurality of panels 10, 11 and 12 form one side of a wall form and corresponding panels 10a, 11a etc. form the opposite wall of the form. In this assembly each panel comprises a facing sheet 14 which is of such common materials as plywood, or composition board faced on a wood backing. Each facing sheet is positioned between two metal edge strips 15 and 16. The strips 15 and 16 substantially cover the edges of the sheet 14 and extend perpendicular to the sheet beyond one face thereof. The edge strips 15 and 16 have flanges 17 and 18 along the edges thereof which are most remote from the sheet 14. These flanges are turned in toward each other.

The sheets 14 are backed up by a plurality of cross bars 19, 20, 21, 22, 23, 24 and 25 which extend between the edge strips 15 and 16. The spacing of the cross bars is such as to give the greatest support to the sheet 14 near the bottom of the form because that is where the greatest expansive force of the fluid concrete is encountered. The cross bars 19 and 25 are so constructed as to protect the end edges of the sheet 14. Preferably the cross bars 19 and 25 are composite bars, made up of angle iron 26 which is joined to the edge strips 15 and 16 and a rectangular wooden bar 27 which sets between the angle iron 26 and the sheet 14. The cross bars 21, 22 and 23 may well be made entirely of wood. The cross bars 21 and 24 however, are made of angle irons which have their vertical flanges 20a and 24a engaging the sheet 14 and their horizontal flanges 20b and 24b extending outwardly away from the sheet 14.

45 The angle irons 20, 24 and 26 are welded to the end strips 15 and 16 to provide a rectangular rigid frame of metal. The wooden cross bars such as 21, 22, 23 and 27 are fastened by nails 42 through holes in the flanges 17 and 18 and the sheet 14 is fastened to these wood bars by screws or nails. The end strips 15 and 16 have stops 28 punched out at intervals throughout their length to engage against the back of the sheet 14. It will be noted that the entire panel is free of any projecting parts that could be readily bent in handling and transporting it.

50 The constructions by which the panels are assembled together to form two spaced apart walls is quite simple. The end strips 15 and 16 have aligned apertures 29 and 30 at spaced intervals throughout their length. The lowermost apertures 29 and 30 are directly below the angle iron cross bar 24 and the uppermost apertures 29 and 30 are directly below the angle iron cross bar 20. The apertures 30 in the end strip 16 hold headed pins 31 when the panels are separated for handling. The headed pins 31 have slots 32 therein for the reception of wedges 33. The wedges 33 are driven in tightly enough to secure the pins 31 in place so that they will not be lost in transportation. The angle iron cross bars 20 and 24 have slots 34 therein through which the wedges 33 pass to secure the pins 31, located at this point. For the wedges that are not adjacent to the cross bars 20 and 24, I provide small blocks 35 on the inner face of the end strip 16 to serve as stops to keep the wedges 33 from swinging out away from the sheets 14.

70 When the panels are being assembled, a tie strip 36 is used in combination with the panels to tie the two

opposite walls together. These tie strips may be used with each of the headed pins 31, if desired. In assembling the wall, the tie strip is laid between two adjacent end strips 15 and 16, just above the apertures for the pin 31. The tie strips hook over the end strips 15 and 16 as illustrated at 37 and 38 in Figure 3 of the drawings. Also each end of the tie strips is folded over on itself as indicated at 39 and 40, for the purpose which will presently appear. Notches 41 are provided in the flanges 18 of the end strip 16 to receive the bent over ends 37 and 38 of the tie strip 36. When the tie strips 36 are in place and the wedges 33 are driven down, they clamp the tie strips tightly against the adjacent face of the end strip 16. When the force, due to the weight of the fluid concrete, tends to spread the two form walls apart, the tie strip 36 will of course, have a force exerted on it, tending to force it to slip with respect to the end strips 15 and 16, and to work out from the wedges 33. The construction illustrated and just described, effectively prevents slipping of the tie strips. The clamping between the end strips 15 and 16 alone is not enough, nor is the bend at 37 and 38 enough to prevent slipping. However, the friction at these points, plus the clamping action of the wedge and the opposition offered by the folded over ends 39 and 40 of the tie strips gives adequate holding power to prevent spreading of the walls up to the strength of the tie themselves.

It is believed that the nature and advantages of my invention will be apparent from the foregoing description.

Having thus described my invention, I claim:

1. A panel assembly for constructing forms for pouring concrete walls comprising in combination, a pair of opposed groups of like panels arranged edge to edge wherein each panel comprises a rectangular facing sheet, metal edge strips secured to said sheet and extending along two opposite edges of the sheet, the edge strips covering the edges of said sheet and extending perpendicular to the sheet beyond one face thereof, the strips having in-turned flanges along their edges most remote from the sheet, spaced cross bars connected to the strips and extending from one strip to the other between the flanges and the sheet and providing backing support for said sheet, the strips having apertures therein adjacent to certain of said cross bars, the apertures in one strip being aligned with the apertures in the opposite strip whereby two like panels may be placed edge to edge with the apertures in their abutting side strips in registration to receive a fastening member, headed pins having their shanks extending through the registered apertures, the shanks of said pins having slots therein to receive wedges for drawing the side strips of two edge to edge panels together, wedges inserted in said slots, the adjacent cross bars having slots at one end also receiving the wedges whereby to prevent turning of the wedges away from the sheets, tie strips extending between the two groups of panels and between the side strips of edgewise meeting panels in each group at levels between the headed pins and the adjacent slotted cross bar, the ends of each tie strip being bent around the side strip adjacent to the wedge and passing between the wedge and the side strip, the ends of the tie strips being folded over upon the tie strips between the wedges and the adjacent surface of the sheet.

2. The invention defined in claim 1, in which the in-turned flanges of the side strips are cut away where the tie strips are bent around the side strips.

3. A panel for use in setting up forms for pouring

concrete walls comprising a rectangular facing sheet, metal edge strips secured to said sheet and extending along two opposite edges of the sheet, the edge strips substantially covering the edges of said sheet and being wider than the thickness of the sheet to extend perpendicular to the sheet beyond one face thereof, the strips having flanges at their edges most remote from the sheet, the flanges of the strips extending toward each other, the strips having spaced apertures therein between their flanges and the facing sheet, spaced cross bars connecting the end strips and bearing against the sheet to provide backing support for the sheet, certain of said cross bars having wedge guide slots wherein adjacent to one of the end strips and said certain cross bars being adjacent to but spaced from an aperture in said one end strip, headed pins carried in the apertures of the last named end strip and having wedge slots therein to receive and hold wedges extending through said guide slots, the flange having a tie strip guide notch therein between each slotted cross bar and the adjacent pin receiving aperture, and wedges in said guide slots and extending through the slots in the pins to secure the pins to the panel.

4. A panel for use in setting up forms for pouring concrete walls comprising rectangular facing sheet, metal edge strips secured to said sheet and extending along two opposite edges of the sheet, the edge strips substantially covering the edges of said sheet and being wider than the thickness of the sheet to extend perpendicular to the sheet beyond one face thereof, the strips having flanges at their edges most remote from the sheet, the flanges of the strips extending toward each other, the strips having spaced apertures therein between said flanges and the facing sheet, spaced cross bars connecting the end strips and bearing against the sheet to provide backing support for the sheet, headed pins carried in the apertures of one of said end strips with their heads on the outer face of the strips, the pins having wedge receiving slots therein, wedges passing through said slots and securing the pins to said end strip, and wedge guide members on the inner face of said strip spaced from the aperture and preventing the wedges and pins from rotating in the aperture, the flange having a tie strip guide notch between the aperture and the adjacent wedge guide member.

5. The invention defined in claim 1 in which the end strips have other aligned apertures therein spaced from the first named apertures and from said cross bars, headed pins having slotted shanks extending through said other aligned apertures, wedges in said slotted shanks, blocks on the end strips holding the last named wedges against rotation, and tie strips like said first named tie strips bent around the side strip adjacent to the last named wedges between the blocks and the pins and clamped in place by said wedges.
